UNITED STATES PATENT OFFICE

2,389,502

FIRE EXTINGUISHER

Glenn G. Griswold and Floyd J. Lee, East Los Angeles, Calif., assignors to J. Leonard Hull, Los Angeles, Calif.

Application November 7, 1941, Serial No. 418,144

13 Claims. (Cl. 169—32)

Our present invention relates to fire extinguishers, and particularly to means for initiating the same.

The invention disclosed herein is an improvement of the fire extinguisher disclosed on our former patent application, Serial Number 406,278, filed August 11, 1941.

One of the principal objects of the improvements of this invention is to provide a novel means for gripping and collapsing a shatterable receptacle from a remote position, and more specifically when the receptacle is enclosed or concealed in a tight or sealed container.

Another important object of this invention is to provide a fire extinguisher in which separate reacting chemicals are contained in separate shatterable receptacles, and in which novel means are provided for easily and effectively shattering the receptacles from the outside of the main container for releasing the chemicals therein.

An important object also is the provision of novel and simple means for easily forcing jaws or bars to grip tightly and clamp, over its whole length, the receptacle to be broken, and thereby quickly discharge the contents of the receptacle.

A further object of this invention is to provide a fire extinguisher embodying the foregoing features in a compact unit which may be easily attached to or inserted into a main container, and which may also be easily removed therefrom, for reloading the unit with fresh chemicals.

With these and other objects in view, we have devised a fire extinguisher having certain novel features of construction, combination, and arrangement of parts and portions, as will be hereinafter described in detail and particularly set forth in the appended claims, reference being had to the accompanying drawing and to the characters of reference thereon, which form a part of this application in which:

Fig. 1 is a side elevation of a fire extinguisher embodying the various features of our invention, portions being broken away and in section to facilitate the illustration;

Fig. 2 is a plan view thereof;

Fig. 3 is an enlarged sectional view thereof, showing particularly the chemical-containing cartridge therefor, parts being also shown broken away and in section to facilitate the illustration;

Fig. 4 is a fragmentary elevation of the lower portion of the cartridge taken at a right angle to that shown in Fig. 3;

Figs. 5 and 6 are transverse sections taken through 5—5 and 6—6 of Fig. 3; and

Fig. 7 is a transverse section taken through 7—7 of Fig. 4.

Our fire extinguisher, as in the former application, is enclosed in a main container or tank 1, having a discharge hose 2 connected to the upper portion of the container or tank 1. At the upper end of the container is a filling opening 1^a, which is normally closed by a ring screw cap 3 having a ring or handwheel 3^a to facilitate the securing or removal of the cap.

Within the container is stored a supply of solvent 11, which in this instance is water, for reacting with the other chemicals, as will be described hereafter.

At the upper end and axial portion of the container 1 are placed the chemicals which are to be mixed with the water to form the fire extinguishing agent. These chemicals, designated 12 and 13, are contained in a cylindrical tube 14, all forming part of a cartridge A. This cartridge is carried by, or suspended from, the cap 3. The lower end of the cartridge extends below the surface of the water 11. The cartridge is so arranged in the container 1 that it may be easily removed and replaced by another, as will be hereinafter more clearly described.

The tube 14 is made of readily destructible or shatterable material, such as thin glass, with a closed bottom end. The top of the tube is hermetically sealed by any suitable seal, such as by paraffin 15. The tube is also divided intermediate its ends, by a paraffin wad 16, into two separate lower and upper chambers or receptacles 14^a and 14^b, which are hermetically separated. In these receptacles are placed, respectively, the chemicals 12 and 13. The lower chemical 12 may be sodium bicarbonate (NaHCO₃), and the chemical in the upper receptacle 13 may be oxalic acid (H₂C₂O₄·2H₂O), both preferably in dry powdered form.

The bottom end of the tube 14 rests on spring 21 carried by the cap 22 which is removably secured, by bayonet locking means 23, to the lower end of an open cylindrical cage frame 24. The upper end of the cage frame is screwably secured to a boss 3^b at the underside of and coaxial with the cap 3.

Over the outer side of the cage frame is removably placed a cylindrical wire mesh cage 25. The lower end of the cage may be secured to the cap 22, and is preferably removed therewith from the cage frame. The upper end of the cage may abut a collar 24^a near the upper end of the cage frame 24.

At the underside of the cap 3 are links or rocker

arms 31 which are pivoted intermediate their ends on lugs 32^a extending downwardly from a support 32 which, in this instance, is a nut, as will be hereinafter described. The links or rocker arms are radially arranged with respect to the axis of the cap 3, the tube 14, and cage frame 24. On the outer ends of the rocker arms are pivotally suspended the tube gripping and shattering bars 33, there being two of such bars which are located at diametrically opposite sides of the tube. The lower ends of the bars are located with respect to each other by a split resilient band 34.

The bars 33 are forced inwardly as they are raised by rocking the links or rocker arms 31. The means for forcing the bars 33 inwardly consists of a plurality of pairs of wedges 35 and 36, the former carried by the cage frame 24 and the latter by the bars 33. The cage 24 has a plurality of transverse rings 24^b, which are spaced apart and secured together by longitudinal straps 24^c. Each of the rings are provided at opposite sides, and specifically at the intersection of the straps, with the wedges 35. The wedges 36 are carried on the outer sides of the bars 33 opposite the wedges 35, with which they engage. As the bars 33 are raised, the wedges 35 force the wedges 36 inwardly, and thereby force inwardly the bars 33. To permit such inward movement of the bars, the bearing or pivot portions of the rocker arms are longitudinal slots 31^a.

The inner ends of the rocker arms 31 are engaged by a wide or disc-shaped head 41^a at the inner end of the plunger 41, which is reciprocally mounted at the axial portion of an externally threaded sleeve 42 which in turn is secured in the axial portion of the cap 3. The head 42^a at the outer end of the sleeve may be drawn tightly against the upper side of the cap 3 by the nut 32 mentioned above, or, as shown, the sleeve may be screwed into the cap and may be locked in place by the nut 32.

The plunger 41 is sealed with respect to the sleeve 42 by means of a stuffing box 43, as shown.

The plunger 41 is adapted to be forced inwardly by means of a cam 51^a at one end of a lever 51, said end being pivoted between lugs 42^b which extend upwardly from the opposite sides of the sleeve 42. The free or opposite end of the lever 51 extends beyond the ring 3^a of the cap 3, and is provided beyond the ring 3^a with a loop portion 51^b to facilitate the manipulation of the lever.

It will be noted that the cross-sections of the inner sides of the bars or jaws 33 are concave or undercut, as indicated by 33^a in Figs. 6 and 7, for receiving and more securely gripping the tube 14, to prevent movement and breaking of the tube during ordinary handling of the fire extinguisher.

It will also be noted that the head or lower end of the cap 22 is open, or is covered with wire mesh 22^a, to allow water or other solvent also to enter from below.

Though we have shown and described a particular construction, combination, and arrangement of parts and portions, we do not wish to be limited to the same, but desire to include in the scope of our invention, the construction, combination, and arrangement, substantially as set forth in the appended claims.

We claim:

1. A fire extinguisher, comprising a pressure container, a plurality of axially aligned receptacles extending into the container from the wall thereof, a different chemical in each receptacle, and means extending outwardly beyond the wall

from a position adjacent said receptacles, said means comprising bars extending longitudinally of the receptacles, and spaced circumferentially from each other with respect to the receptacles, and means for contracting said bars around the receptacles and thereby rupturing the same.

2. A fire extinguisher, comprising a pressure container, a plunger at one end of the container, links pivotally mounted within said container at 10 said end, said links being adapted to be rocked by the plunger, a plurality of bars, one depending from each of the links, a shatterable chemical container located between the bars, and means for contracting the bars with respect to each 15 other when the same are moved longitudinally.

3. A fire extinguisher, comprising a pressure container, a plunger at one end of the container, links pivotally mounted within said container at said end, said links being adapted to be rocked by the plunger, a plurality of bars, one depending from each of the links, a foraminous enclosure 20 depending within the container around the bars, a shatterable chemical receptacle located between the bars and carried by the enclosure, 25 and wedge means between the bars and the wall of the enclosure for contracting the bars with respect to each other when the same are moved longitudinally.

4. A fire extinguisher, comprising a pressure 30 container having an opening, a cap for the opening, a plurality of axially aligned receptacles supported by the cap in the container, a different gas-forming chemical in each receptacle, said chemicals being capable of reacting to create a 35 gas, and means extending through the cap from the outside of the container rupturing all of the receptacles, said means comprising bars extending longitudinally of the receptacles, and spaced circumferentially from each other with respect 40 to the receptacles, and means for contracting said bars around the receptacles and thereby rupturing the same.

5. A fire extinguisher, comprising a pressure 45 container having an opening at one end, a cap for the opening, a plunger reciprocal axially within the cap, links pivotally mounted on the inside of the cap, said links being adapted to be rocked by the plunger, a plurality of bars, one depending from each of the links, a shatterable 50 chemical container located between the bars, and means for contracting the bars with respect to each other when the same are moved longitudinally.

6. A fire extinguisher, comprising a pressure 55 container having an opening at one end, a cap for the opening, a plunger reciprocally mounted within and at the axial portion of the cap, links pivotally mounted on the inside of the cap, said links being adapted to be rocked by the plunger, 60 a plurality of bars, one depending from each of the links, a foraminous enclosure depending from the cap around the bars, a shatterable chemical receptacle located between the bars and carried by the enclosure, and wedge means between the 65 bars and the wall of the enclosure for contracting the bars with respect to each other when the same are moved longitudinally.

7. A fire extinguisher, comprising a pressure 70 container having an opening at one end, a cap for the opening, a plunger reciprocally mounted within and at the axial portion of the cap, links pivoted intermediate their ends on the inside of the cap, said links radiating outwardly from the axis of said cap and adapted to be rocked by the plunger, a plurality of bars, one depending from 75

the outer end of each link, a shatterable chemical receptacle located between the bars and substantially coaxial with the plunger and supported by the cap, and means for contracting the bars with respect to each other for rupturing the receptacle when the plunger is moved longitudinally.

8. A fire extinguisher, comprising a pressure container having an opening at one end, a cap for the opening, a plunger reciprocally mounted within and at the axial portion of the cap, links pivoted intermediate their ends on the inside of the cap, said links radiating outwardly from the axis of said cap and adapted to be rocked by the plunger, a plurality of bars, one depending from the outer end of each link, a foraminous enclosure depending from the cap around the bars, a shatterable chemical receptacle located between the bars and carried by the enclosure, and means for contracting the bars with respect to each other when the same are moved longitudinally.

9. A fire extinguisher, comprising a pressure container, a shatterable chemical receptacle located within the container, a plurality of bars extending longitudinally of the receptacle and spaced circumferentially from each other with respect to the receptacle, and means on the outside of the container for contracting the bars around the receptacle and thereby rupturing the same.

10. A fire extinguisher, comprising a pressure container having an opening at one end, a cap for the opening, a plunger reciprocally mounted within and at the axial portion of the cap, a link pivotally mounted on the inside of the cap and adapted to be rocked by the plunger, a bar depending from the link, a shatterable chemical receptacle located adjacent the bar, and means for forcing the bar into engagement with the receptacle, when the bar is moved longitudinally by the link, for shattering the receptacle.

5 11. A fire extinguisher, comprising a pressure container having an opening at one end, a cap for the opening, a plunger reciprocally mounted within and at the axial portion of the cap, a link pivotally mounted on the inside of the cap and adapted to be rocked by the plunger, a bar depending from the link, a foraminous enclosure depending within the container around the bar, a shatterable chemical receptacle carried by the enclosure and located adjacent the bar, and means in association with the bar and the wall of the enclosure for causing the bar to engage the receptacle, when the bar is moved longitudinally by the link, for shattering the receptacle.

10 12. A fire extinguisher, comprising a pressure container, a plunger at one end of the container, links pivotally mounted within said container at said end, said links being adapted to be rocked by the plunger, a plurality of bars, one connected to each of the links, a shatterable chemical container located between the bars, and means for contracting the bars with respect to each other when the same are moved longitudinally.

15 13. A fire extinguisher, comprising a pressure container, a plunger at one end of the container, links pivotally mounted within said container at said end, said links being adapted to be rocked by the plunger, a plurality of bars, one connected to each of the links, a foraminous enclosure depending within the container around the bars, a shatterable chemical receptacle located between the bars and carried by the enclosure, and wedge means between the bars and the wall of the enclosure for contracting the bars with respect to each other when the same are moved longitudinally.
